UNITED STATES PATENT OFFICE.

WILLIAM F. MARSHALL, OF NEW YORK, N. Y.

PENCIL.

1,286,699.

Specification of Letters Patent.

Patented Dec. 3, 1918.

Application filed October 21, 1916. Serial No. 126,837.

To all whom it may concern:

Be it known that I, WILLIAM F. MARSHALL, a citizen of the United States of America, residing at the borough of Manhattan, in the city, county, and State of New York, have invented certain new and useful Improvements in Pencils, of which the following is a specification, reference being had to the accompanying drawings.

10 This invention relates to improvements in pencils and particularly to improvements in that part of the pencil commonly known as the nose-piece, by which the lead is held; and an object of this invention is to cheapen 15 the construction of the nose-piece and to simplify the manufacture of the same without any sacrifice of efficiency.

In the drawings illustrating the principle 20 of this invention and the best mode now known to me of applying that principle, Figure 1 is an elevation, partly in section, of a pencil provided with my new nose-piece; Fig. 2 is a section on the line 2—2 of Fig. 1, the handle being omitted; Figs. 3, 4 and 25 5 are sections on the lines 3—3, 4—4 and 5—5, respectively, of Fig. 2.

The tubular handle *a* is of the same kind as has heretofore been used. In the mouth *b* of this handle *a*, there is inserted the base 30 end of the nose-piece *c*. This nose-piece is split or two-part and consists of two substantially identical halves *d*, *e*, one of which is shown in Fig. 2. These halves *d*, *e*, are made of sheet metal and are stamped, by 35 which process of manufacture cheapness of manufacture is attained. The exteriors of the halves *d*, *e*, are formed with threads *f* to admit of the engagement of the halves *d*, *e*, by the cap *g*, which engagement is

effected by screwing the cap *g* upon the 40 halves *d*, *e*, of the nose-piece *c*, these halves being held in proper relation to admit of the operation being carried out. It is to be observed that the longitudinal edges *h*, *i*, of each half of the nose-piece *c* are flanged, 45 as shown at *h'*, Figs. 3 and 4 and at *i'*, Figs. 3 and 5. The flanges *h'*, *i'*, enable the halves *d*, *e*, of the nose-piece *c* to be held firmly in assembled relation and prevent the opposed edges *h*, *i*, from slipping 50 past each other, when the structure is being assembled. A collar *j* formed on the nose-piece *c* serves as an abutment or stop to limit the inward travel of the cap *g*, the movement of which over the nose-piece *c* 55 serves to release and tighten the jaws *k* with respect to the lead *m* passing therebetween.

I claim:

A split, thin, sheet-metal pencil nose-piece 60 comprising two parts each of which is formed with a lead-gripping jaw, said parts being formed exteriorly with means for engagement with the pencil-cap and with flanges that extend along the longitudinal 65 edges of the parts and are arranged to prevent the same from slipping out of registry with each other when they are being assembled and locked in registry with each other by engagement with the pencil-cap. 70

Signed at the borough of Manhattan, city, county and State of New York, this 20th day of October, A. D., 1916, in the presence of the two undersigned witnesses.

WILLIAM F. MARSHALL.

Witnesses:

FRANCIS H. BALDWIN,
M. E. WOARDELL.
